UNITED STATES PATENT OFFICE.

EUGENE N. YEHLE, OF MARYVILLE, MISSOURI.

DEVICE FOR CLAMPING SHADES TO ROLLERS.

Application filed May 4, 1925. Serial No. 27,761.

To all whom it may concern:

Be it known that I, EUGENE N. YEHLE, a citizen of the United States, and a resident of Maryville, county of Nodaway, State of Missouri, have invented a certain new and useful Improvement in Devices for Clamping Shades to Rollers, of which the following is a complete specification.

The present invention relates to devices for attaching window shades or the like to rollers, and aims to provide a novel and improved device of this character which will permit or facilitate the ready attachment or removal of the shades to and from the rollers whenever repairs or renewals are required.

The primary object of the invention is to provide an extremely simple and inexpensive device for facilitating the ready and convenient shade attaching and removing function, and the use of which affords not only a neater but also a more efficient and secure attachment of the shade to the roller than is afforded by the ordinary method of attachment.

For carrying out this principal object of the invention, I make use of a tubular split sleeve which is adapted to be conveniently and quickly applied to the shade roller in clamping relation thereto, by virtue of the spring character of the metal forming the sleeve, and to one of the longitudinal edges of the sleeve a convenient connection is made to one of the end edges of the shade for attaching these parts permanently together.

With this general object in view the invention will now be described by reference to the accompanying drawing illustrating suitable forms of construction which I have devised for embodying the proposed improvements, after which those features and combinations deemed to be novel will be particularly set forth and claimed.

In the drawing:—

Figure 1 is an elevation, partly broken away, showing a shade and roller provided with an attachment constructed in accordance with the present invention;

Figure 2 is a perspective view of the same;

Figure 3 is a transverse section taken on the line III—III of Figure 1, on an enlarged scale;

Figure 4 is an end view of the attaching device, with a portion of the shade attached thereto;

Figure 5 is a perspective view showing an end portion of the roller with a modified

form of connection between the shade and attaching device; and

Figure 6 is a perspective view showing a slightly modified form of the attaching member.

Referring now to the drawing in detail, this illustrates the invention in connection with the usual form of curtain or shade roller 10 to which the shade 11 is usually secured by means of tacks, or the like. In the present case, I make use of a novel form of detachable connection between the shade 11 and roller 10, and for this purpose employ a roller clamping sleeve 12 of a diameter approaching that of the roller 10, to which it is adapted to be firmly clamped by virtue of the spring action of the metal alone, although it may be additionally secured to the roller by means of a tack or nail 14 as indicated in Figures 1 and 3. As illustrated, the sleeve 12 is of split form, and one of its longitudinal edges is securely clamped to one of the end edges of the shade by means of a double rolled flange 16 embracing said end edge of the shade, as clearly shown in Figure 3, the metal forming the edge of the sleeve being firmly pressed and clamped to the edge of the shade or curtain by any suitable means or method, to form this secure connection with as little bulge or protuberance as possible, so that no appreciable bulging appearance will be produced in the shade when wound up on the roller.

In Figure 5 is simply illustrated a modified form of connection between the shade 11 and the clamping sleeve 12, the end of the shade being provided with a folded strip of gummed linen 18, making an adhesive connection to the end of the shade, and the strip of linen 18 in turn being clamped to one of the edges of the sleeve 12, in the same manner as illustrated for making the connection between the shade and member 12 direct, as in Figures 1 to 4.

A modified form of construction for the roller clamping member is shown in Figure 6, the same comprising a split tubular sleeve 12', with one of its longitudinal edges cut out to provide spring fingers 20 for yieldingly gripping the roller when the device is applied thereto. The end of the shade 11 is attached to the other longitudinal edge of the member 12' in the same manner as already explained.

By means of this construction, it will be seen that the shade 11, when provided with

the clamping member 12 or 12', may be readily and conveniently attached or removed by simply slipping the clamping device on or off the roller, in an obvious manner. This 5 eliminates entirely the necessity of manipulating tacks or nails for securing the shade to the roller, and it is apparent that when retained upon the roller by the improved device, the shade cannot be jerked off by 10 any ordinary pulling upon the shade, or detached by any accidental disengagement from the roller. There is the further advantage that the new device provides an improved and more accurate means of attaching the shade to the roller due to the 15 continuous connection being made entirely across its end edge, thus insuring an exact alinement of the edge the whole length of the roller.

20 With the use of this form of connection between the shade and the roller, it is also apparent that I eliminate entirely the cost of roller replacement, when a new shade becomes necessary, since the purchaser needs 25 only order a shade of the proper size, and the clamping device 12 may be supplied with the shade, so that the purchaser can make his own replacement by merely removing the old shade and applying the new one, which 30 requires merely sliding the member 12 or 12' endwise upon the roller. The dealer can supply the clamping devices with the shades with much less expense than the rollers as 35 is done in the present practice, and the clamping devices can be prepared simply

as required, cutting them to a length according to the width of shade ordered. The method of connecting the shade to the device 12 or 12' by means of the clamping bead or double roll 16 is immaterial, and this 40 can be accomplished by the usual methods employed for producing this crimping of the metal.

While I have illustrated and described what I now regard as the preferred form of 45 the construction for embodying the invention, I wish to reserve the right to make such changes and modifications as may fairly fall within the scope of the appended 50 claims.

What I claim is:

1. A device for attaching window shades to rollers, comprising a split tubular sleeve of spring sheet metal adapted for removable clamping engagement with the roller, one 55 of the longitudinal edges of said sleeve being rolled into clamping and retaining engagement with one of the end edges of the shade.

2. A device for attaching window shades 60 to rollers, comprising a split tubular sleeve of spring sheet metal adapted for removable clamping engagement with the roller, one of the end edges of the window shade being connected with one of the longitudinal edges 65 of said sleeve.

In witness whereof I hereunto affix my signature.

EUGENE N. YEHLE.
